Primary Examiner — Dominic Simone(74) Attorney, Agent, or Firm — Morgan, Lewis & Bockius LLP(57) CLAIM

An ornamental design for a split-sole shoe, as shown and described.

DESCRIPTION

FIG. 1 is a perspective view of our new design of a split-sole shoe;

FIG. 2 is a first side view of the design of FIG. 1;

FIG. 3 is a second side view of the design of FIG. 1;

FIG. 4 is a top view of the design of FIG. 1;

FIG. 5 is a bottom view of the design of FIG. 1;

FIG. 6 is a front view of the design of FIG. 1;

FIG. 7 is a back view of the design of FIG. 1; and,

FIG. 8 is another perspective view of the design of FIG. 1, the perspective view illustrating the split-sole shoe when it is placed in a folded configuration.

The broken lines illustrating the stripe and half moon patch in the above described Figures are for illustrative purposes only and form no part of the claimed design.
